UNITED STATES PATENT OFFICE.

JOHN W. SCHULLER, OF CEDAR FALLS, IOWA.

PANTS.

SPECIFICATION forming part of Letters Patent No. 241,731, dated May 17, 1881.

Application filed April 9, 1881. (No model.)

To all whom it may concern:

Be it known that I, JOHN WM. SCHULLER, a citizen of the United States, resident at Cedar Falls, in the county of Black Hawk and State of Iowa, have invented certain new and useful Improvements in Pants; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification, in which—

15 Figure 1 is a front view, showing the flap open. Fig. 2 is a similar view, showing it shut. This invention has relation to the construction of trousers or pantaloons; and it consists in providing, in connection with a closed front 20 and a flap extending from the center of the front to one side, an inner flap extending from the side to the center of the front, carrying the waistband, and provided with a double set of buttons, one set being placed a little in advance 25 of the other, so that they may be used interchangeably in securing the outer flap and the suspenders, as hereinafter shown and described.

The object of this invention is chiefly to provide 30 a pair of pantaloons which can be readily enlarged or contracted about the abdomen without wrinkling, thereby enabling the wearer to adjust them with regard to his personal comfort without producing a distorted or slovenly appearance.

In the accompanying drawings, the letter *a* designates the waistband, which is made in the usual manner and provided with the front fastening, *b*, as shown in the drawings, or with 40 button-hole fastening, as may be desired. The front is closed, as shown, and on one side is connected to the waistband permanently, in the usual manner. On the other side an external flap, *c*, is formed, constituting part of 45 the front, but disconnected from the waistband and at the side as far down as may be necessary for convenience and to allow for the adjustment, the edge being finished neatly and strongly. The upper margin of the flap is provided 50 with two button-holes, *d d*, sufficiently distant from each other to serve as means for

connecting the flap to the suspender-buttons *e e*, which are placed on the waistband. If the side margin, *f*, of the flap is made longer than is usual in pocket-openings, a button and button-hole may be provided near its lower end, to hold it in position when a contracted adjustment is effected.

Connected to the back of the pantalon, on the side by the side seam, and to the waistband above, is an inner piece or flap, *g*, which may carry the pocket. This inner flap extends toward the center of the front, to protect the wearer, and is provided at its upper portion with two buttons, *h h*, placed a sufficient distance from each other to suit the button-holes *d d* of the outer flap, *c*, each button *h* being a little forward or rearward, as may be desirable, of the corresponding suspender-button *e*, but below the same.

It is evident that the flap *c* can be readily buttoned either to the upper set of buttons, *e e*, or to the lower set, *h h*, producing an enlargement or contraction, according to requirement, the suspender being fastened to the set 75 of buttons not in use in securing the flap. The flap may be arranged on either side, and is designed to serve the comfort of the wearer without detracting from the neat appearance of the garment. The construction also enables the 80 wearer to adjust his underclothes with facility.

Having described this invention, what I claim, and desire to secure by Letters Patent, is—

In a pair of pantaloons having a closed front 85 and a central-fastening waistband, the outer side flap, *c*, centrally secured and having free top and side margins, and button-holes *d d*, the inner flap, *g*, secured at the side and top and extending toward the center, and the two 90 sets of buttons *e e* and *h h*, arranged one set somewhat in advance of the other, and interchangeable with relation to the suspender and the button-holes of the flap, substantially as specified.

In testimony whereof I affix my signature in presence of two witnesses.

JOHN WILLIAM SCHULLER.
